UNITED STATES PATENT OFFICE

GEORGE B. PICKOP, OF NEW HAVEN, CONNECTICUT, ASSIGNOR TO MALLEABLE IRON FITTINGS COMPANY, OF BRANFORD, CONNECTICUT

VIBRATOR HOUSING

Application filed October 13, 1923. Serial No. 668,449.

My invention relates to vibrator housings and more particularly to a device adapted to support or carry a vibrator, and provided with means by which it may be securely and rigidly attached to the object, such as a core box, flask or the like, which is to be vibrated. It is sometimes difficult in foundry practice to remove castings from the boxes or flasks in which they are made and very often it occurs that sand, dirt or other matter adheres to the walls of the articles and must be removed usually by pounding on the walls or by a scraping operation. As the boxes or flasks are quite often damaged in this manner, and as it is a more or less tedious operation, it has been found to be much more expedient to use vibrators operated by compressed air to vibrate the boxes or flasks and dislodge the material therefrom.

In the past, vibrator supports have sometimes been provided with hooks or eyes adapted to embrace a lug or trunnion secured to the core box, flask or other article with which the vibrator is intended to be used, but such a securing means is inefficient and not very effective for the reason that the connection between the vibrator support and trunnion is not rigid and, therefore, a considerable part of the vibration will be absorbed or lost in this loose connection and will not be imparted to the box or flask.

One object of my invention is to overcome the disadvantages referred to above and to provide a vibrator support with means by which it may be rigidly secured to the device upon which the vibrator is intended to act and which connection at the same time may be quickly made and also quickly detached.

Another object of my invention is to provide an improved vibrator supporting member which may not only be rigidly attached to the box or flask with which it is to be used, but which is also adapted to have the vibrator itself rigidly secured thereto.

A still further object of my invention is to provide the vibrator supporting member with a loop in the form of a hook or eye by which it may be quickly attached to a lug or trunnion on the box or flask to be

vibrated and to provide a wedging member designed to enter the loop and urge the wall of the latter into firm and secure engagement with the lug or trunnion to make a rigid connection between the parts.

To these and other ends the invention consists in the novel features and combination of parts to be hereinafter described and claimed.

In the accompanying drawings:

Fig. 1 is a perspective view of a foundry flask supported by vibrator housings embodying my invention;

Fig. 2 is a top plan view of the housing;

Fig. 3 is a side elevational view of the same;

Fig. 4 is an end view;

Fig. 5 is a view similar to Fig. 2 showing a slightly modified form of construction;

Fig. 6 is a fragmentary side elevational view of one end of the housing shown in Fig. 5;

Fig. 7 is an enlarged detailed view of the key or wedge member used in connection with the housing shown in Figs. 1 to 4;

Fig. 8 is a view similar to Fig. 7, showing the wedge member used in the modification shown in Figs. 5 and 6, and,

Fig. 9 is an enlarged detailed view of one of the flask trunnions.

In Fig. 1 of the accompanying drawings I have shown the vibrator housings 10 and 11 attached at their lower ends to a foundry flask 12, from which the sand may be removed when the vibrators are set in operation. The flask 12 may, of course, be a foundry flask of the usual or any preferred form and may be provided with means by which the vibrator housings may be attached thereto in a convenient and suitable manner. In the form shown, the flask is provided upon each end with lugs or trunnions 13 adapted to be embraced by a loop in the end of the housing.

The vibrator housings 10 and 11 may be identical in form and each is provided with a U shaped body portion having a base 14 and side members 15 and 16. Between these side members is formed a U shaped seat for the

55

vibrator mechanism 17, the casing of which is provided with end heads 18 and 19 having laterally projecting lugs 20 and 21 which may be secured to the ends 15 and 16 of the housing by the bolts 22 and 23.

It will be observed that the vibrator mechanism is arranged by machining or otherwise to fit snugly between the inner faces of the side members 15 and 16, so that the ends 18 and 19 will be held securely in place by these members and so that there will be no likelihood of these ends being dislodged or loosened by the action of the vibrator plunger.

The housing is provided with end wings 25 and 26 which may be provided with loops or jaws in the form of eyes or hooks so that the vibrator may be conveniently attached to the various devices with which it is used. Upon the wing 25 is shown an eye or ring 27 which in the application of my invention shown in Fig. 1, is adapted to receive a hook or the like 28. The wing 26 is provided with a hook 29 which is adapted to receive the trunnion 13 on the foundry flask 12. It will, of course, be apparent that if the trunnion or lug 13 is merely received loosely in the hook a considerable part of the vibration will be lost, and for this reason the sand or casting will not be shaken from the flask as readily as will be the case when a rigid connection is made between the vibrator housing and the flask.

For this purpose, I have provided the wing 26 with a T shaped keyway 30, in which is movably mounted a tapered key 31, which may be moved across the hook after the latter has been slipped over the trunnion 13, to wedge the trunnion tightly between the lower surface of the key and the lower portion of the hook. The key 31 is provided with side flanges 32 and 33 so that it is T shaped in cross section, the flanges serving to properly guide the key in the correspondingly shaped keyway 30. The key may also be provided with stops 34 and 35, by which its movement transversely of the hook 29 may be limited. As has been stated, the lower edge of the key or wedge member 31 is inclined so that the key is wedge shaped and will have a wedging action when moved in its guideway to rigidly clamp the trunnion against the hook of the housing. Adjacent the front end of the key the latter may be cut away as shown at 37, so as to provide for the entrance of the trunnion into the hook.

In Figs. 5 and 6 I have shown a somewhat modified form of my invention wherein the housing 10 instead of being provided with a hook upon the end which is adapted to be attached to the flask, is provided with a closed ring 40. The ring in this case is adapted to be slipped over the end of the trunnion, which is thereupon clamped rigidly in place by means of the tapered key 41, the action of which is similar to the key 31 already described. The key may be recessed as shown

at 42, adjacent its front end, to admit the trunnion or lug 13 into the ring 40. After the trunnion has been received in the ring, the wall of the latter will enter to some extent the annular groove 43 therein, and will then permit the key to be moved transversely so that its tapered lower side will wedge the trunnion securely against the side of the ring 40.

It will be apparent that in both forms of my invention which I have illustrated, I have provided the vibrator housing with a loop to embrace a lug or trunnion on the device which is to be shaken by the vibrators, and have provided means by which the housing may be secured rigidly to the foundry flask or core box with which it is used, so that the efficiency of the vibrator will be greatly increased.

It will be seen that, as shown in Fig. 1, the device to be vibrated or flask 12, is suspended from the hook 44, which may, of course, if desired, be attached to a crane or suitable means for handling the flask. The vibrators and housings 10 and 11 are included in the connecting or suspending means between the hook and the flask, so that they constitute a part of the supporting means for the flask. By providing the vibrator housings as part of the suspending means for the devices to be vibrated, it will be apparent that these devices may be handled expeditiously and conveniently and moved from place to place while the vibrator is connected thereto. Moreover, by providing a rigid and firm connection between the vibrator housings and the flask, and at the same time a connection which is capable of being readily attached to and detached from the flask, that the device will be very efficient in operation and will result in a saving of time on the part of the operatives.

While I have shown and described some embodiments of my invention, it will be understood that it is not to be limited to all the details shown but is capable of modification and variation within the spirit of the invention and within the scope of the appended claims.

What I claim is:

1. A vibrator support comprising a member having a body portion providing a seat for a vibrator, a vibrator comprising a casing and end heads secured thereto, means on said heads for securing the vibrator to the support, and means at one end of the support to embrace a part of an object to be vibrated.

2. A housing having means to support a vibrator casing and provided with an attaching loop and a wedging member mounted in the housing to move across the loop for the purpose described.

3. A housing having means to support a vibrator casing and provided with a loop by which it may be attached to the member upon

- which the vibrator is designed to act, and a key movably mounted in the housing and cooperating with the wall of the attaching loop to rigidly secure the housing to said member.
5. A vibrator support comprising a member having a body portion, means at one end of said body portion by which it may be suspended, and a loop at the opposite end thereof for securing it to an object to be vibrated, and a clamping key cooperating with the wall of the loop.
10. A housing having means to support a vibrator casing and provided with an attaching loop, and wedging means movably mounted in the housing to decrease the effective size of said loop for the purpose described.
15. A vibrating support comprising a member having a body portion, means at one end of said body portion by which it may be suspended, and a loop at the opposite end thereof adapted to embrace a part of an object to be vibrated, and means to hold said part rigidly within the loop to transmit the vibrations to said part.
20. A housing having means to support a vibrator casing and provided with an attaching loop designed to embrace a part of a member to be vibrated, and a wedge shaped key to hold the said part rigidly in the loop for the purpose described.
25. A housing having means to support a vibrator casing and provided with an attaching loop, and a wedge shaped member slidably mounted in a part of the housing and movable across the loop to vary the effective size thereof.
30. A housing having means to support a vibrator casing and provided with an attaching loop, and a wedge shaped member slidably mounted in a part of the housing and movable across the loop to vary the effective size thereof, said wedge shaped member having a recessed portion to permit the reception of a member within the loop.
35. A housing member having a U-shaped body portion providing a seat adapted to receive a vibrator and end wings by which it may be secured in position, one of said wings being provided with a loop, a guideway in said wing disposed transversely of said loop and a key member slidably mounted in said guideway.
40. A vibrator housing having means to support a vibrator casing and provided with an end wing by which it may be attached to adjacent elements, said wing being provided with a loop and a wedging key slidably mounted in a guideway in the wing and movable across the loop to decrease the effective size thereof.
45. A vibrator housing provided with an attaching loop to receive a lug or the like on a member to be vibrated, and a wedging member slidably mounted in the loop and adapted to be moved to position to clamp said lug se-
- curely against a part of the loop, said housing being provided with a seat for supporting a vibrator casing and having end walls between which the casing is snugly received.
50. A vibrator support comprising a member having a body portion, means at one end of said body portion by which it may be suspended and a loop at the opposite end thereof to receive a trunnion or the like on an object to be vibrated, and means to clamp said trunnion rigidly in position within the loop to suspend said object therefrom and to transmit vibrations thereto.
55. A housing having means to support a vibrator casing and provided with an attaching loop, and a wedge member mounted in the housing to move across the loop for the purpose described, and means to limit the movement of said member.
60. A housing provided with a seat for supporting a vibrator casing, said seat having end walls, a vibrator casing having end heads secured thereto, and means on said heads for detachably securing the casing in said seat with said heads fitting snugly against said end walls whereby the heads are reinforced by the end walls of the seat of the housing.
65. A vibrator support comprising a body portion having opposed shoulders thereon, a vibrator casing having end heads secured thereto and a vibrator reciprocably mounted therein, means on said heads for securing said casing to said support with its heads abutting said shoulders, and means for attaching said support to an object to be vibrated.
70. In a vibrating device, means for suspending a suspending means, and means for firmly securing one end of the suspending means to an object to be vibrated, said means including a loop adapted to receive a part of the object to be vibrated, and a wedging member to firmly secure said part to the loop.
75. In a vibrating device, means for suspending a vibrator, and means for firmly securing one end of the vibrator to an object to be vibrated, said means including a loop adapted to receive a part of the object, and means to rigidly secure said part to the loop.
80. In a vibrating device, a flexible suspending means, a rigid vibrator supporting member secured to said means, means for detachably securing a vibrator to said member, and means for rigidly attaching said member to an object to be vibrated, whereby said object is suspended by the supporting member.
85. In a vibrating device, a vibrator support having means by which it may be suspended, and means by which it may be attached to an object to be vibrated, a vibrator including a casing having end heads secured thereto, projecting lugs on said heads, and means to secure said lugs to said support.
90. A vibrator comprising a casing having end heads secured thereto, and a piston reciprocably mounted therein, and means se-

cured to said end heads for supporting the vibrator and for embracing a part of a member to be vibrated.

22. In combination, a vibrator comprising a casing having end heads secured thereto, supporting means for the vibrator comprising a member embracing the casing lengthwise thereof and secured to said end heads, and means for securing the vibrator to an object to be vibrated.

23. A vibrator comprising a casing having end heads secured thereto, and means for supporting said vibrator and securing it to an object to be vibrated comprising a member extending lengthwise of the body of the vibrator and secured to the end heads thereof.

In witness whereof, I have hereunto set my hand this 11th day of October, 1923.

GEORGE B. PICKOP.
